UNITED STATES PATENT OFFICE.

JOSEPH H. ALLEN, OF EL PASO, TEXAS.

COLLAR ATTACHMENT.

1,224,828.

Specification of Letters Patent.

Patented May 1, 1917.

Application filed February 13, 1915. Serial No. 8,096.

To all whom it may concern:

Be it known that I, JOSEPH H. ALLEN, a citizen of the United States, residing at El Paso, in the county of El Paso and State of Texas, have invented new and useful Improvements in Collar Attachments, of which the following is a specification.

This invention relates to collar attachments and more particularly to attachments 10 adapted to be used in connection with folding or turn-down collars.

Most of these collars are provided with a locking flap adapted to hold the parts close together in the front but these locking flaps 15 are ineffective for this purpose in many instances, and when a gap is once formed at the front of the collar in any manner it is seldom restored to normal or closed position unless the wearer adjusts his necktie and 20 draws the parts of the collar together. Furthermore, it is found that to secure any semblance of an effectively closed front collar it is necessary to use an abnormally large locking flap which is difficult to insert beneath the folds of the collar after the free 25 ends have been buttoned together. It is, therefore, the object of this invention to provide simple and efficient means which may be conveniently attached to the collar 30 and which will at all times hold the collar properly closed independent of the action of the necktie or scarf.

Further objects of the invention will appear as the following description is read in 35 connection with the accompanying drawing, which forms a part of this application, and in which:—

Figure 1 is a front elevation of a collar with parts broken away and showing in 40 dotted lines the position of the attachment when in operation.

Fig. 2 is a perspective view with parts broken away and showing the device attached thereto and in inactive position.

Fig. 3 is a transverse sectional view taken 45 through the collar and showing the manner of engagement of the device with the locking flap.

Referring more particularly to the drawing, wherein I have illustrated an ordinary

turn down collar, 1 shows the inner wall of the collar, 2 the inner button hole flap and 3 the outer or locking flap arranged to extend beneath the folds upon the opposite side of the collar when in operative position 55 upon the wearer's neck.

The attachment generally indicated at 4 is constructed of a single piece of spring wire of relatively fine gauge and having one terminal formed to provide a penetrating 60 pin 5 which is adapted to be inserted through the fabric of the inner flap 2, as shown, to hold the device attached to said flap and which is curved to conform to the general curvature of the collar. At the 65 inner end of the pin the wire is bent vertically and back upon itself in the form of a loop which produces a shoulder 6 for limiting the inward movement of the pin and also for preventing the pin from turning in 70 the flap. Depending from the loop is a relatively large bowed spring 7 which terminates in a laterally projecting penetrating prong 8 adapted to stick into the inner wall of the flap 3, as will be readily understood. 75 In placing the device in operative position the fore finger is caused to engage the lower end of the bowed spring 7 which is forced upwardly, thus moving the prong 8 toward the shoulder 6. When considerable tension 80 has been placed upon the spring the flap 3 is forced into engagement with the prong 8 which causes said prong to enter the flap 3, while the spring is under tension. This will effectively hold the collar in closed position 85 independent of whether the scarf is drawn taut around the collar or whether the flaps are buttoned together or not.

What is claimed is:—

A device of the kind described composed 90 of a spring wire member, said wire member being shaped to provide a straight shank, said shank being bent back to form a loop extending in the same direction as itself and terminating in a pin formed at an angle 95 upon one side of the loop whereby a shoulder is formed between the shank and pin, said member being also shaped to provide a relatively large bowed spring upon its shank the inner end of which curves laterally be- 100

yond said shoulder in the direction of said pin and its free end curving around the shank on the opposite side of said shoulder and spaced from said shank, said spring 5 having a prong formed at its outermost end disposed substantially in a plane at right angles to the axis of said shank.

In testimony whereof I affix my signature in presence of two witnesses.

JOSEPH H. ALLEN.
